INVENTOR

UNITED STATES PATENT OFFICE.

CHARLES E. DEY, OF DENVER, COLORADO.

DESIGN FOR AN INDICATOR-COVER.

SPECIFICATION forming part of Design No. 16,590, dated March 30, 1886.

Application filed June 1, 1885. Serial No. 167,352. Term of patent 3½ years.

To all whom it may concern:

Be it known that I, CHARLES E. DEY, a citizen of the United States, residing at Denver, in the county of Arapahoe and State of Colorado, have invented and produced a new and original Design for Indicator-Covers for Electro-Magnetic Annunciators, of which the following is a specification, reference being had to the accompanying drawing, forming 10 part thereof.

The leading feature of my design consists in the representation of a plain surface having curved outlines, the lower extremity, A, being of a circular shape, diminishing as it 15 comes nearer the center of the figure. The upper or other end portion, B, is also circular in form, but smaller in size than the lower end. The sides are formed of arcs, C and D, of

circles, the curves being inward as to the surface, and the junctions of said curves forming 20 projecting points.

What I claim, and desire to secure by Letters Patent, is—

A design for an indicator-cover, consisting of the representation of a plain surface having curved outlines, the end portions, A and B, being of circular form of different sizes, and the sides being arcs of circles curved inward as to the surface, and having their junctions forming projecting points, substantially as 25 30 shown and described.

CHARLES E. DEY.
